US0D1056396S

(12) **United States Design Patent** (10) **Patent No.:** **US D1,056,396 S**
(45) **Date of Patent:** **** Dec. 31, 2024**

(54) **RAMP**

(71) Applicant: **Shenzhen Andejian Technology Co., Ltd.**, Shenzhen (CN)

(72) Inventor: **Jihong Hu**, Shenzhen (CN)

(73) Assignee: **Shenzhen Andejian Technology Co., Ltd.**, Shenzhen (CN)

(**) Term: **15 Years**

(21) Appl. No.: **29/825,201**

(22) Filed: **Jan. 29, 2022**

(51) LOC (14) Cl. **12-05**

(52) U.S. Cl.

USPC **D34/32**

(57) **CLAIM**

The ornamental design for a ramp, as shown and described.

DESCRIPTION

FIG. 1 is a perspective view of a ramp, showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken line showing of the ramp is for the purpose of illustrating article and forms no part of the claimed design.

1 Claim, 8 Drawing Sheets
